SADDLE HASSOCK

Irving Sheinfeld and Harold Garber,
Atlantic City, N. J.

Application November 8, 1951, Serial No. 17,322

Term of patent 7 years

(Cl. D15—8)

To all whom it may concern:

Be it known that we, Irving Sheinfeld and Harold Garber, both citizens of the United States, both residing at Atlantic City, in the county of Atlantic and State of New Jersey, have invented a new, original, and ornamental Design for a Saddle Hassock, of which the following is a specification, reference being had to the accompanying drawing, forming part thereof.

In the drawing,

Fig. 1 is a front elevation of a saddle hassock, showing our new design,

Fig. 2 is a side elevation thereof,

Fig. 3 is a top plan view thereof,

Fig. 4 is a bottom plan view thereof, and

Fig. 5 is a rear elevation thereof.

We claim:

The ornamental design for a saddle hassock, as shown.

IRVING SHEINFELD.
HAROLD GARBER.
